Specification for Design.

Patented Apr. 2, 1918.

Application filed February 4, 1918. Serial No. 215,365. Term of patent 14 years.

To all whom it may concern:

Be it known that I, ADAM E. JOHNSON, a citizen of the United States, and resident of Jersey City, in the county of Hudson and State of New Jersey, have invented a new, original, and ornamental Design for a Yarn-Holder for Knitting, of which the following is a specification, reference being had to the accompanying drawing, forming part thereof.

An embodiment of my new design for a

yarn holder for knitting is shown in the accompanying drawing, in which—

Figure 1 represents a top plan view of my yarn holder for knitting, and

Fig. 2 represents a side elevation of the same.

I claim:

The ornamental design for a yarn holder for knitting, substantially as shown.

ADAM E. JOHNSON.
